UNITED STATES PATENT OFFICE.

HENRY A. WISE WOOD, OF NEW YORK, N. Y., ASSIGNOR TO THE CAMPBELL PRINTING PRESS & MANUFACTURING COMPANY, OF NEW YORK, N. Y., A CORPORATION OF NEW YORK.

PRINTING-MACHINE.

SPECIFICATION forming part of Letters Patent No. 693,203, dated February 11, 1902.

Application filed April 6, 1893. Renewed July 3, 1901. Serial No. 67,014. (No model.)

To all whom it may concern:

Be it known that I, HENRY A. WISE WOOD, a citizen of the United States, residing at New York, in the county of New York and State 5 of New York, have invented a new and useful Improvement in Printing-Machines, of which the following is a specification.

The aim of this invention is to improve the parts of what are known in the art as "cylinder printing-presses" and "cylinder perfecting printing-presses." My invention is especially adapted to such a press in which a web 10 is printed upon.

I will now describe my improvements as 15 applied to a traveling-cylinder web-printing press or more particularly to a traveling-cylinder web-perfecting printing-press, it being understood, as hereinafter described, that my improvements are not limited to such specific 20 form of press.

Referring to the accompanying four sheets of drawings, Figure 1 is a diagrammatic view 25 of one form of press with my improvements applied thereto, showing the feed of the web around the impression-cylinders taking place. Fig. 2 is a similar diagrammatic view showing the cylinders as printing. Figs. 3 and 4 are enlarged elevations showing the particular web-guiding mechanism used in 30 connection with one of the cylinders. Figs. 5 and 6 are views of one of the cylinders, the cylinder being shown as off and on the forms on the bed, respectively, illustrating a modified form of my invention. Figs. 7 and 8 are 35 views similar to Figs. 5 and 6, illustrating a further modification of my device. Figs. 9 and 10 are similar views illustrating still another modification, and Fig. 11 is a perspective view of one of the parts used in the modification shown in Figs. 9 and 10.

The action of the traveling-cylinder printing-press, whether the same prints on one side of the web or two sides of the web, is well understood in the art and, briefly stated, is as 45 follows: The web is held stationary while the printing takes place and is pressed onto a form placed upon the stationary bed by means of the traveling impression-cylinder. Then when the traveling impression-cylinder is

thrown out of impression or when the same is 50 not in contact with the form upon the bed the proper length of web is shifted around the impression-cylinder, so that at the next printing movement of the impression-cylinder a fresh portion of the web can be printed. 55 It will be seen that the shifting action of the web necessarily draws the web around the impression-cylinder, and hence there must be considerable friction between the impression-cylinder and the web. This friction renders 60 the feeding action hard, and the friction on the second impression-cylinder in a perfecting-press is very apt to smut or blur the first-printed side of the web.

The aim of my invention is, broadly, to provide means whereby the web is cleared of or separated from the impression-cylinder when the feed takes place, so that when the web is intermittently shifted the same will not have to be dragged around the surface of the impression-cylinder. 65

My invention can be applied to any form of traveling-cylinder printing-press, whether the same employs one cylinder and a bed or a plurality of cylinders and beds, and my 70 invention can be applied to all the cylinders or to any one of the cylinders of such form of press.

I have shown in the diagrammatic views one form of press simply to illustrate the way 75 the web is cleared of or separated from the impression-cylinders when the feed takes place. I have shown in these diagrams substantially the same arrangement of printing mechanisms as is shown in Letters Patent to John H. Stonemetz, No. 376,053, granted January 3, 1888, and a perfecting form of press, it being understood, of course, that the beds may be arranged in any of the well-known manners without departing from the scope of my 80 invention, and, further, that my invention may be applied to the single cylinder of a single printing-press or simply to the second cylinder of a perfecting form of press; but I prefer in most cases to apply my invention to all the 85 cylinders in a press, so that the feed can easily take place. I contemplate, however, as before stated, in some cases only apply- 90 95

ing my invention to the second cylinder of a perfecting form of traveling-cylinder printing-press, so as to prevent smut or offset of the web on the second impression-cylinder 5 when the web is pulled or shifted around such second impression-cylinder.

Referring now to the diagrams, I will describe the form of press that I have chosen to illustrate the application of my invention.

10 Referring to Sheets 1 and 2 of the drawings, it will be seen that A and B represent two stationary form-beds, which are arranged end to end or in substantially the same horizontal plane, and that C and D represent two traveling impression-cylinders adapted to coact, respectively, with forms placed upon the beds A and B.

E represents in outline the reciprocating carriage in which the impression-cylinders 20 and guides are mounted, the carriage E being simply shown in outline to indicate which parts travel and not being a correct representation of the carriage, and this carriage E is supposed to be reciprocated forward and backward parallel with the form-beds by any of the usual driving mechanisms, not necessary here to show or describe at length. Mounted in the carriage at each side of each impression-cylinder are the form-rollers F F, which 25 are used to properly ink the forms in the well-known manner.

G represents the web-roll, from which the web may be led in the usual manner into the press. From the web-roll G the web may be 30 led in through the continuously - running rollers 15, 16, and 17 around the looping feeding-in roller 18, which is mounted in arms 19, pivoted on shaft 20, and these arms 19 may carry rollers 21, which bear against cams 22, 35 mounted on shaft 23, which shaft 23 is preferably revolved twice for each complete forward and backward movement of the impression-cylinders, whereby the proper length of web will be fed out when the impression-cylinders reverse in either direction. The rollers 21 may be kept normally against the cams 22 by means of springs 24, as shown. 40 From the looping-roller 18 the web passes around the stationary roller 25 and then to the roller 26, mounted in the end of the framing. From the roller 26 the web is led around the rollers or guides 260 and 27, mounted in the carriage beneath the impression-cylinder C, and then up around the rollers or guides 28 45 and 29, also mounted in the carriage E. From the guide or roller 29 the web is carried across the press to the usual stationary adjustable register-roll 30, and from the roll 30 the web passes back to the rollers or guides 31 and 32, 50 mounted in the carriage E, then under the impression-cylinder D, then up around the rollers or guides 33 and 34, also mounted in the carriage E, to the stationary guide or roller 35. From the roller 35 the web is led 55 down around the stationary guides or rollers 36 and 37, around the looping delivery-roller 38, which may be mounted in arms 39, piv-

oted on the shaft 40, and these arms 39 may have rollers 41, which can bear on the cams 42, mounted on the shaft 43, which shaft 43 70 may be geared to turn synchronously with the shaft 23, but in the opposite direction. The rollers 41 may be kept normally against the cams 42 by means of springs 44. From the looping-roller 38 the web is led continuously 75 out of the press by means of the continuously - running delivery - rollers 51, 52, and 53.

Any suitable inking apparatus may be used to supply ink to the form-rollers and may be 80 mounted on either or both ends of the beds, as desired. The preferred form of inking apparatus consists of fountains H, vibrating ductor-rollers 45, drum-cylinders 46, carrier-rollers 47 and 48, and the drum-cylinders 49 85 and 50, which drum-cylinders are arranged a distance apart substantially equal to the distance between the form-rollers F F at each side of each impression-cylinder.

As shown in the drawings, an inking apparatus 90 is arranged at each end of each bed and so that a full discharge of ink will be given to the form-rollers on each side of the impression-cylinders when the impression-cylinders are off the form-beds in either direction. Any other suitable or desirable inking mechanism can be used.

The form-rollers F may be mounted in suitable hangers f, attached to the carriage E, or in any other suitable manner, so as to drop 100 down on the drum-cylinders 49 and 50 as the carriage reverses in either direction.

The preferred form of my inking apparatus, which is shown in Sheets 1 and 2 of the drawings, is a great improvement in this class 105 of presses in that a full charge of ink is supplied to both of the form-inking rollers at each end of the bed.

In the ordinary traveling-cylinder press as the same is arranged in its best form to-day 110 ink is supplied to the form-rollers on each side of the impression-cylinder, either to both form-rollers when they are off the bed in one direction or to one roller at each end of the bed.

My improved invention of supplying a full charge of ink to the form-rollers at each side of the impression-cylinder when they are off the form in either direction gives really a double inking for each impression. Thus, 120 for example, taking the case of the impression-cylinder C, it will be seen that as the same moves to the right the form on the bed A is inked by the form-inking roller F to the left of the impression-cylinder C, which form-roller F has just received a full charge or supply of ink from the left-hand drum-cylinder 50. When the impression-cylinder is 125 off the form-bed at the right, the left-hand form-roller F will receive another full charge or supply of ink from the right-hand drum 50, and as the impression-cylinder moves back over the form upon the bed A the form will 130 again be inked. Thus there will be two full

ink deposits on the form for each impression, the form-inking roller at the right of the impression-cylinder C acting in the same way in connection with the drum-cylinders 49. In 5 other words, the form-inking rollers on both sides of the impression-cylinder are supplied with a full charge of ink at both ends of the form, which gives a double ink-supply to the form, thus enabling my press to be applied 10 to a nice and fine class of bookwork. I am aware of the inking apparatus shown in Letters Patent to Stonemetz, before referred to, and also of Letters Patent to J. L. Cox, July 5, 1892, No. 478,503. In the Stone- 15 metz device the forms are inked only once for each two impressions. In the Cox device the forms are inked once for each impression, while in my improved device the forms are fully inked twice for every impression, 20 thus adapting my press to the nicer grades of work. This inking apparatus forms a radical departure and improvement in this line of presses.

The organization of the press thus de- 25 scribed is well understood, and by means of the same two perfected sheets will be printed for each complete forward - and - backward movement of the impression-cylinders. The action of the feeding mechanism in this press 30 is also well understood, and the looping-rollers and continuously-running feeding-in and feeding-out rollers are so driven and timed that when the impression-cylinders are trav- 35 eling over the forms the web in the press will remain stationary, but so that when the im- 40 pression-cylinders are off the forms in either direction a fresh length of web will be pulled forward through the press, the web at all times running continuously into and out of

It will be seen in the common organization of a press of this character that when the web is intermittently shifted the same will be dragged around the impression-cylinders, 45 as when the carriage reverses as the feed takes place the impression-cylinders are nearly stationary, whereby there will be a great deal of friction between the web and impression-cylinders.

50 My invention consists, broadly, in clearing the web out of contact with the impression-cylinder while the intermittent feed around the same takes place and in allowing the impression-cylinder to bear on the same while the printing is done.

In the diagrammatic views, Figs. 1 and 2, I have shown my invention as applied to both impression-cylinders, so that when the feed takes place the web will not touch either im- 60 pression-cylinder; but, as before stated, in some presses I contemplate only applying my device to the second impression-cylinder of a perfecting form of traveling-cylinder press.

In the diagrams shown in Fig. 1 I have 65 shown the guides on each side of each impression-cylinder lowered, so as to move the web clear of the impression-cylinders while

the feed takes place, the feed thus taking place while the web is clear of the impression-cylinders.

In Fig. 2 the guides are shown as in their normal position and the impression-cylinders as bearing on the web and printing.

There are many ways in which the web may be moved clear of the impression-cylinders 75 during the feed and allowed to come back on the impression-cylinders when the printing is to be done.

The preferred form of my invention is shown in Figs. 3 and 4 as applied to the second im- 80 pression-cylinder D, it being understood, of course, that the same device is applied, if desired, to the first impression-cylinder C. In this device the guides or rollers 32 and 33, by which the web is led under the second im- 85 pression-cylinder D, are shown as mounted in arms 63 and 64, which arms 63 and 64 are journaled or hung on the shaft c of the im- 90 pression-cylinder D, whereby the rollers 32 and 33 can be moved on arcs about the cen- 95 ter of the impression-cylinder D: On the sides of the frames which constitute the car- 100 riage E are mounted frames K. These frames K are mounted on the frames of the carriage so as to be vertically movable thereon, and 105 one convenient way to so mount the frames K is to cut a slot k in the same, which slot 110 embraces and fits on the shaft c. Above and below the slot k are also formed slots, as 54 and 55, into which slot screws, as 56 and 57, fit, these screws being tapped into the car- 115 riage-frames. By this means it will be seen that the frames K are mounted so as to be vertically movable on the carriage-frames. It is understood, of course, that two frames K 120 are used in connection with each impression-cylinder on each of the carriage-frames, it being unnecessary to show the other frame K, the same being exactly the same as the frame K shown. These frames K have studs 650 se- 125 cured to the same, which studs connect by links 65 and 66 to the arms 63 and 64, which carry rollers or guides 32 and 33. Secured in the lower end of the frame K are the studs 58, on which are journaled rollers 59. These 130 rollers 59 are arranged so as to bear on suitable guides 60, formed or arranged on the sides of the bed, as shown, and these guide- 135 ways 60 have suitable inclines 61 at each end of the bed, as shown, and I preferably ar- range above these cam portions of the guide-ways guards or cams 62. As shown, the roll- 140 ers 31 and 34 are arranged rigidly in the car- 145 riage-frames. The way this form of my in- 150 vention acts is as follows: When the im- 155 pression-cylinders run off the forms upon the bed, the rollers 59 will run down the incline 61 and also under the guards or cams 62. This will pull the frames K down and will move the 160 rollers or guides 32 and 33 downward, so as to 165 move the web clear of the impression-cylinder D, as shown in Fig. 3. Now when the im- 170 pression-cylinder is off the form, as shown, the intermittent web-shifting mechanism acts

and pulls the web forward; but as this feed takes place it will be seen that there will be no slip between the impression-cylinder and the web, as the web does not touch the impression-cylinder. As the cylinder moves back toward the forms the rolls 59 will run up the cams 61, and the rolls or guides 32 and 33 will be moved to their normal positions or to the positions shown in Fig. 4, when the web will again come into contact with the impression-cylinder D. This action of course takes place at each end of the bed.

In Fig. 4 the impression - cylinder D is shown as in contact with forms placed upon the bed B and as printing. The guide 60 is extended across the form-bed, so that during the entire printing operation the guides 32 and 33 are held in their normal positions.

In some cases when it is desired to have very nice work I intend to connect the guides or cams 62, as by a guide 620, as shown in dotted lines in Fig. 3, so that there will be a continuous groove, as 600, for the rollers 59. The guard 62 is useful in that as the feed takes place a tension is put on the web and the guard 62 will prevent the guides being lifted by the feeding action of the web. Another advantage which results from this form of my invention is that the device will also act as a web-tensioning device—that is, when the guides 32 and 33 are lowered, as shown in Fig. 3, the web will be slightly slackened, so that the feed can take place easily, but when the guides 32 and 33 are extended upwardly or raised to their normal positions, as shown in Fig. 4, the slack will be taken up and the web will be kept very taut in the machine during the printing operation, so that a perfect register will be obtained. Thus it will be seen that my device acts also as a web-tensioning device as well as a device for automatically moving the web clear of the impression-cylinder while the feed takes place.

The construction with the first impression-cylinder C in the preferred form of my device, where it is arranged to also manipulate the web about the first impression-cylinder in the same manner, is just the same as that shown in Figs. 3 and 4 and need not be again here shown or described.

My invention could obviously be applied to a press in which the printing only takes place in one direction, as shown in Letters Patent to W. P. Kidder, No. 291,521, granted January 8, 1884; but the form of press that I preferably use is the one in which the feed takes place when the impression-cylinders are thrown out of impression in either direction or at each end of the bed.

It is of course obvious that my invention can be applied to a single printing-press—that is, to a printing-press in which one bed and one cylinder are used—the invention being simply applied to the cylinder of that form of machine.

In Figs. 5 and 6 I have shown a modification of my device. In this modification the

four rollers or guides 31, 32, 33, and 34 are arranged in frames K², which are mounted on the carriage-frames E in the same manner as the frames K of the device shown in Figs. 3 and 4, and these frames K² have the same operating mechanism as shown in Figs. 3 and 4. With this modification when the impression-cylinder is off the form-bed, as shown in Fig. 7; 5, the frames K² and the guides or rollers 31, 32, 33, and 34 will be lowered, so that the web can be shifted through the press without contact with the impression - cylinder. When the impression-cylinder, however, is moved so as to engage the forms, the rolls or guides mounted in the frames K² will be raised, as shown in Fig. 6, so that the impression-cylinder will bear upon the web, as shown.

In Figs. 7 and 8 I have shown a further modification. In this modification the rollers or guides 31, 32, 33, and 34 are fixed or journaled in the carriage-frames E, as shown. On the carriage-frames E are mounted frames K³, which are mounted so as to be capable of vertical motion upon the frames, and one convenient way to mount these frames K³ is to slot the frames, as at 54 and 55, and to use screws 56 and 57, as in the previous modification. These frames K³ have formed or secured thereto racks, as 70, and these racks 70 mesh into teeth 72, secured or formed on arms 71, which arms 71 are journaled or hung on the shaft c of the impression-cylinder D. These arms 71 carry between them a shield 73, which is made out of smooth or polished metal, and the whole is so arranged that when the shield is swung down that the shield will lift the web off the impression-cylinder between the guides 32 and 33. In this modification the cam-slot 610 has to be turned so as to move the frames K³ upwardly instead of downwardly, as in the previous device, and with this modification I preferably use a strip 621, which extends the entire length of the bed. The frames K³ have studs 58 and rollers 59, as in the previous device, which run in the groove 600, formed by the guides 60 and 621. With this modification the action is as follows: When the impression-cylinder runs off the forms in either direction, the frames K³ will be moved by means of the cam 610, and by this means the shield 73 will be swung under the impression-cylinder and will move the web clear of the impression-cylinder, so that the feed of the web can take place without contact of the impression - cylinder. Then when the impression-cylinder moves so as to again engage the form the frames K³ are lowered and the shield 73 is withdrawn from under the impression-cylinder D and the impression-cylinder can bear on the web to present the same to the forms, as shown in Fig. 8. While this is not the preferred form of my device, still the same possesses many advantages over the ordinary construction, where the web is pulled bodily forward and in contact with the impression-cylinder. The impression-cylinders in most cases are cov-

ered with a rubber or felt blanket, and the web necessarily runs very hard if shifted in contact with the impression-cylinder; but by using the device shown in this modification 5 the web is lifted clear of the impression-cylinder and is moved over a smooth metallic surface, over which a web can be moved in a very easy manner, as is well known in connection with formers and turner-bars.

10 In Figs. 9, 10, and 11 I have shown another modification. This modification is arranged and mounted similarly to the modification shown in Figs. 5 and 6; but instead of using the two rollers 32 and 33 I use a shield or 15 guard L, which is cut away, as at l, so that the impression-cylinder can bear on the web through this cut-away portion. This guard or shield L is preferably turned in on the ends, as at l', and around the hole l, as at l'', so that it will present a smooth and curved 20 surface for the web. In Fig. 9 the guides 31 and 34 and the shield or guard L are shown as lowered and the web as moved clear of the impression-cylinder, so that the feed can take 25 place without contact of the web with the impression-cylinder. In Fig. 10 the guides or rollers 31 and 34 and the shield L are shown as raised, so that the impression-cylinder can bear on the web through the hole l and properly 30 press the web onto the forms. By this means it will also be seen that the web can be shifted without contact with the impression-cylinder. The mounting and arrangement for this shield L is just the same as that 35 for the rollers 32 and 33 of the modification shown in Figs. 5 and 6 and need not be specifically shown and described. Thus it will be seen that I have provided a device which greatly simplifies and eases the action of the 40 feed and also a device which greatly lessens the smut of the web. The adjusting mechanism for adjusting the impression cylinder or cylinders relatively to the forms is not shown in this case, as many forms of the same are 45 well understood and may be arranged in the press so as not to interfere with the peculiar web-manipulating devices before described.

I contemplate and the scope of my invention covers the application of my improved 50 invention to any impression-cylinder around which a web may be shifted and, broadly, can be applied to an impression-cylinder which is stationary and with which coacts a reciprocating form-bed. Also my invention is applicable to the form of press shown in my application filed July 27, 1892, Serial No. 441,365, 55 in which two impression-cylinders are used to coact with each form-bed. Also my invention can be applied and used in connection with the double single printing-cylinders shown in my application filed April 6, 1893, Serial No. 469,324, or, again, in connection with the double cylinders shown in applications filed by Louis W. Southgate April 6, 60 65 1893, Serial Nos. 469,322 and 469,323. In these last cases two impression-cylinders are shown as coacting with a single form-bed.

As shown, the details of my invention can be greatly modified by a skilled mechanic without departing from the scope of my invention, and I have shown a number of modifications and the preferred form of my invention to enable the scope of my invention to be 70 fully understood.

Having thus fully described my invention, 75 what I claim, and desire to secure by Letters Patent, is—

1. The combination in a web-printing press of a form-bed, an impression-cylinder coacting therewith, means for intermittently shifting the web relatively to the impression-cylinder, and means for separating the web and the impression-cylinder when the shift takes place. 80

2. The combination in a web-perfecting printing-press of two form-beds, an impression-cylinder coacting with each form-bed, means for intermittently shifting the web relatively to the impression-cylinders, and means for separating the web and impression-cylinders when the shift takes place. 85 90

3. The combination in a web-printing press of a form-bed, a traveling impression-cylinder coacting therewith, means for intermittently shifting the web relatively to the impression-cylinder, and means for separating the web and the impression-cylinder, when the feed takes place. 95

4. The combination in a web-printing press of two form-beds, a traveling impression-cylinder coacting with each form-bed, means for intermittently shifting the web relatively to the impression-cylinders, and means for separating the web and the second impression-cylinder when the feed takes place. 100 105

5. The combination in a web-printing press of two form-beds, a traveling impression-cylinder coacting with each form-bed, means for intermittently shifting the web relatively to the impression-cylinders, and means for separating the web and impression-cylinders when the feed takes place. 110

6. The combination in a web-printing press of a form-bed, a traveling impression-cylinder coacting therewith, means for intermittently shifting the web when the impression-cylinder is off the form in either direction, and means for separating the web and the impression-cylinder, when the impression-cylinder is off the form in either direction. 115 120

7. The combination in a web-printing press of two form-beds, a traveling impression-cylinder coacting with each form-bed, means for intermittently shifting the web when the impression-cylinders are off the forms in either 125 direction, and means for separating the web and the second impression-cylinder, when the second impression-cylinder is off the form on the second bed in either direction.

8. The combination in a web-printing press of two form-beds, a traveling impression-cylinder coacting with each form-bed, means for intermittently shifting the web when the impression-cylinders are off the form-beds in 130

either direction, and means for separating the web and the impression-cylinders when the feed takes place.

9. The combination in a web-printing press of a form-bed, a traveling impression-cylinder coacting therewith, guides for leading the web under the impression-cylinder, means for intermittently shifting the web, and means for moving the web away from the impression-cylinder, and slightly slackening the web as the feed takes place.

10. The combination in a web-printing press of two form-beds, a traveling impression-cylinder coacting with each form-bed, guides for leading the web under each impression-cylinder, means for intermittently shifting the web, and means for separating the web and the second impression-cylinder, and slightly slackening the web as the feed takes place.

11. The combination in a web-printing press of a form-bed, a traveling impression-cylinder coacting therewith, guides for directing the web under the impression-cylinder, means for intermittently shifting the web when the impression-cylinder is off the form in either direction, and means for separating the web and the impression-cylinder, and slightly slackening the web as the feed takes place.

12. The combination in a web-printing press of two form-beds, a traveling impression-cylinder coacting with each form-bed, guides for directing the web under each impression-cylinder, means for intermittently shifting the web when the impression-cylinders are out of engagement with the forms in either direction, and means for separating the web and the second impression-cylinder, and slightly slackening the same, as the feed takes place.

13. The combination in a web-printing press of two form-beds, a traveling impression-cylinder coacting with each form-bed, guides for leading the web under each impression-cylinder, means for intermittently shifting the web, and means for separating the web and each impression-cylinder, and slightly slackening the web as the feed takes place.

14. The combination in a web-printing press of two form-beds, a traveling impression-cylinder coacting with each form-bed, guides for leading the web under each impression-cylinder, means for intermittently shifting the web when the impression-cylinders are off the forms in either direction, and means for separating the web and each impression-cylinder, and slightly slackening the web as the feed takes place.

15. The combination in a web-printing press of a form-bed, a traveling carriage carrying an impression-cylinder coacting with the form-bed, guides for directing a web under the impression-cylinder, and means carried by the carriage, adapted to hold the web in contact with the impression-cylinder, while the impression-cylinder coacts with the forms, and to move the web clear of the impression-cylinder when the impression-cylinder is not in contact with the forms.

16. The combination in a web-printing press of two form-beds, a traveling carriage carrying an impression-cylinder coacting with each of said form-beds, and means carried by the carriage adapted to hold the web in contact with the second impression-cylinder when the second impression-cylinder is in engagement with its form, and to move the web out of engagement with the impression-cylinder when the impression-cylinder is not in engagement with its form.

17. The combination in a web-printing press of a form-bed, a traveling carriage carrying an impression-cylinder coacting with the form-bed, guides for directing the web under the impression-cylinder, means for intermittently shifting the web when the impression-cylinder is off the form upon the bed in either direction, and means carried by the carriage adapted to hold the web in contact with the impression-cylinder, while the impression-cylinder engages the form, and to move the web clear of the impression-cylinder when the feed takes place.

18. The combination in a web-printing press of two form-beds, a traveling carriage carrying an impression-cylinder coacting with each form-bed, guides for directing the web under each impression-cylinder, means for intermittently shifting the web when the impression-cylinders are out of engagement with the forms in either direction, and means carried by the carriage adapted to hold the web in contact with the second impression-cylinder, while the second impression-cylinder engages its form, and to move the web clear of the impression-cylinder when the feed takes place.

19. The combination in a web-printing press of two form-beds, a traveling carriage carrying an impression-cylinder coacting with each form-bed, means for intermittently shifting the web when the impression-cylinders are out of contact with the forms in either direction, and means carried by the carriage adapted to hold the web in contact with the impression-cylinders during the printing operation, and to move the web away from the impression-cylinders when the feed takes place.

20. The combination in a web-printing press of the form-bed, the traveling carriage carrying the impression-cylinder coacting with the form-bed, means for moving the web away from the impression-cylinder when the impression-cylinder is not in engagement with the forms, and an actuating mechanism for this means, consisting of vertically-movable frames, and guides having cams adapted to impart a vertical motion to these frames, as the carriage travels.

21. The combination in a web-printing press of the form-bed, the traveling carriage carrying an impression-cylinder coacting with the form-bed, the guides for directing the web under the impression-cylinder, the vertically-movable frames mounted on the carriage, and means for moving the web clear of the impression-cylinder when the impression-cylinder

der is not in contact with the form, this means being actuated from the vertically-movable frames carrying rolls as 59 bearing on guideways 60, which guideways 60 have cams at 5 each end of the bed.

22. The combination in a web-printing press of the form-bed, the traveling carriage carrying an impression-cylinder coacting with the form-bed, the guides 32 and 33 for directing the 10 web under the impression-cylinder, the guides 32 and 33 being mounted in pivoted arms, and means for moving said pivoted arms so that the web will be clear of the impression-cylinder when the impression-cylinder is out of contact with the form in either direction.

23. The combination in a web-printing press of a form-bed, a traveling carriage carrying an impression-cylinder coacting with the form-bed, the pivoted arms 63 and 64 carrying the 20 guides or rollers 32 and 33, which guides are adapted to direct the web under the impression-cylinder, and means for actuating these pivoted arms consisting of the sliding frames having rollers bearing on guides which have 25 cams, said frames being connected to the pivoted arms.

24. The combination in a web-printing press of the form-bed, the traveling carriage carrying an impression-cylinder coacting therewith, 30 the arms 63 and 64 journaled or pivoted on the shaft of the impression-cylinder, said arms carrying guides or rollers 32 and 33 adapted to direct the web under the impression-cylinder, and means for actuating said arms consisting of the vertically-movable frames K, 35 which frames K have rollers 59, and guideways having cams adapted to impart the proper vertical motion to said frames, as the carriage travels.

40 25. The combination in a web-printing press of a form-bed, a traveling carriage carrying an impression-cylinder coacting therewith, the arms 63 and 64 hung on the shaft of the im-

pression-cylinder, and carrying guides or rollers 32 and 33, adapted to direct the web under the impression-cylinder, and the vertically-movable frames K connected by links as 65 and 66 to the pivoted arms, said frames carrying rollers 59, the rollers 59 engaging a suitable guideway as 60, which has cams 61 45 at the ends of the bed, whereby the rollers 32 and 33 will be moved for the purpose described.

26. The combination in a printing-press of a form-bed, a traveling carriage carrying an impression-cylinder co-operating therewith, and form-inking rollers at each side of the impression-cylinder, two rotating ink-drums arranged at each end of the bed, a distance apart substantially equal to the distance between 55 said form-rollers, and means for supplying ink thereto, whereby a full charge of ink will be supplied to both form-inking rollers as the carriage reverses in either direction.

27. The combination in a web-printing press 60 of two form-beds, a traveling carriage carrying an impression-cylinder coacting with each form-bed, and form-rollers arranged at each side of each impression-cylinder, two rotating ink-drums arranged at each end of each bed, 70 each set of drums being a distance apart substantially equal to the distance between the form-inking rollers at each side of one of the impression-cylinders, and means for supplying ink to said drums, the whole so arranged 75 that a full charge of ink will be given to all the form-rollers as the carriage reverses in either direction.

In testimony whereof I have hereunto set my hand in the presence of two subscribing 80 witnesses.

H. A. WISE WOOD.
